Attorney.

UNITED STATES PATENT OFFICE

BENOÎT GRANDJEAN, OF COURBEVOIE, FRANCE

RACK FOR DISK GRAMOPHONE RECORDS

Application filed December 30, 1930, Serial No. 505,562, and in France January 4, 1930.

The present invention relates to a rack for disk gramophone records allowing the instantaneous choice of a record to be made and allowing it to come out of the rack without having to manipulate the other records.

According to the present invention, however, the rack comprises two plates held in parallel spaced relationship by transverse rods or stays, one of said rods having pivotally mounted thereon a plurality of record supporting members, each of which is constituted by sheets of stiff paper or other suitable material, separated by a plurality of independent distance pieces and connected together by metallic eyelets, the arrangement being such that a record slidden into the supporting member rests with one or more points of its periphery touching the distance pieces.

The invention will be further described with reference to an embodiment of construction shown on the accompanying drawing wherein:

Fig. 1 is an elevation of a support according to a first form of execution.

Fig. 2 is a section according to line A—B of Fig. 1,

Fig. 3 is the same support in a different position,

Fig. 4 is a view in perspective of the rack apparatus,

Fig. 5 is a view in perspective of the rack apparatus in its upright position.

According to Figs. 1 and 2 the record supporting member is constituted by two boards 1 and 2 of cardboard or any other appropriate material having the form of a right-angled triangle. These two boards are connected by means of distance pieces 3, 4 and 5 which are fixed by means of metallic eyelets. The record 6 rests on the distance pieces 4 and 5 this latter being integral with the finger 7 serving to manipulate the record supporting member. This latter pivots around the tube 8 passing through the eyelet of the distance piece 3. It is easy to take account that on raising the record supporting member 1 by means of the finger 7, this pivots around

the tube 8 and takes the position indicated dotted in Fig. 1.

The record supporting members 1 constituted as described above are slidden on the tube 8 (Fig. 4) threaded at its two extremities and destined to fix the two parallel plates 9 and 10 constituting the body of the apparatus. The rigidity is obtained furthermore by the tubes 11 and 12 forming the stays of the apparatus. In order to obtain perfect rigidity of these two plates 9 and 10, the edge thereof is turned up at a right angle. They are furthermore provided with ears 13 serving for the transport of the apparatus which may be either introduced into a bag, box or covered with a case.

It is easy to understand, according to the drawing, that the record 6 resting on the distance pieces 4 and 5 can be raised with its support by operating from the bottom to the top on the finger 7.

Each finger 7 is adapted to be placed opposite a graduation of the index 14 constituted by a rectangular band of sheet iron or other material fixed on the tube 12 and on which is glued a band of paper bearing the title of each record. As the records are very thin and as the fingers 7 are thus brought very near one to the other, they can be displaced one with relation to the other by a certain angle so as to be easily operated. It will then be easy to extract any record desired from the rack by simply raising the record supporting member pivoting around the tube 8.

Figs. 3 and 5 show exactly the same record supporting member and the rack apparatus but in the position termed upright. In this case, the record supporting members 1 pivot around the tube 8 which is placed towards the front. The records 6 can be removed from their respective supporting members on manipulating the fingers 7 from top to bottom.

It is to be noticed in the invention that the point of pivoting of the triangular supporting members the angles of which are rounded is placed as low as possible so as to permit the rounded angle of the right-angled

triangle to rest during its rotation on the interior surface of the bottom B.

When a record supporting member is made to pivot towards the front, the upper distance-piece 2, whilst assuring the connection of the two boards of record supporting member serves as the point of support to the record and prevents this latter from rolling towards the front. This distance-piece 2 is formed as one with the manipulating finger 5 fixed by means of an eyelet taking the place of an axis, permitting thus of displacing the fingers one with relation to the other such as hereinbefore described. This displacement of the manipulating fingers permits the easy operation of each record supporting member and the assured reading of the numbers of each record corresponding to the index, these numbers being engraved on the side.

The operation of extracting a record is effected as follows:

The record supporting member of triangular cardboard is drawn towards the front by means of the manipulating finger 5. The centre O of the upper distance-piece 2 describes an arc of a circle as far as O', the record supporting member pivoting around the rod 4. During the greater part of this path, the record maintained between the boards of its record supporting member rests on the lower distance-pieces 2. It leaves the rear distance piece at the moment when its periphery commences to roll upon the surface of the bottom B to be displaced slightly towards the front and to come to rest against the angle A of the bottom of the box and the distance-piece 2 of the apex of the triangle. At this moment, the record 3 is no longer held between its three distance pieces and it is easy thus to withdraw it from its record supporting member.

The method of carrying the invention into effect shown in Fig. 13 has the following characteristics:

1. A record supporting member having the form of a right-angled triangle with rounded angles, which rests on the base of a box containing the records and pivots about the right angle of the triangle on an axis situated as near as possible to the surface of the bottom of the box and in such a way that the records placed between the boards rest on two distance pieces.

2. In that the record is introduced into its record supporting member according to its greatest side, that is to say through the hypotenuse of the right-angled triangle with rounded angles.

3. The rocking of the triangular record supporting member permits the automatic disengagement of the record which comes partially out of the record supporting member, coming to rest on the front edge of the

bottom of the box and the distance piece turned to the front.

In order to prevent the shaking of the records, the box could be provided on the interior with a band of soft rubber or other material C placed at the rear. The cover will also be provided with a band C¹ and at the time of closing of the box, all the records are kept between the two elastic bands C and C¹.

The record supporting member described can serve for the classification of all other similar articles such as coils and boxes of cinematographic films, etc. It is known that the classification of these articles is very difficult to carry into effect. Generally spools and boxes of round form containing cinematographic films are piled up one upon the other, which necessitates considerable manual work to withdraw the spools or the boxes which are at the lower part of these piles. Racks and record supporting members as hereinbefore described lend themselves very well to this classifying. It suffices to separate the two boards of the record supporting member by means of more thick distance-pieces in order to permit the passage of the spools or the boxes containing the films which will be thus classified according to an index and could be withdrawn instantaneously without any other manipulation than that of lowering the record supporting member such as described. It is to be well understood that the rack can serve for the classifying of any other article and that the form of the supports can be varied at will whilst conserving the characteristics of the invention.

It is to be well understood that the invention has only been described by way of example and that its parts can be modified either in their forms, or in their dimensions without changing at all the principles set out above.

Finally, to prevent all deformations of the records the rack can be provided with an appropriate locking device.

What I claim and desire to secure by Letters Patent of the United States of America is:

1. A rack for disk gramophone records comprising two plates held in parallel spaced relationship by transverse stays, a plurality of record supporting members pivotally mounted on one of said stays, said record supporting members being each constituted by sheets of stiff material, distance pieces separating said sheets of stiff material upon which distance pieces the record rests, and metallic eyelets connecting the said sheets of stiff material to said distance pieces.

2. A rack for disk gramophone records according to claim 1, wherein the sheets of stiff material forming the record supporting members are of triangular form, distance pieces located at or near the corners of said

pieces of triangular material and means whereby the eyelets securing said sheets of stiff material to certain of said distance pieces are pivoted upon one of said transverse stays.

3. A rack for disk gramophone records comprising two plates held in parallel spaced relationship by transverse stays, a plurality of record supporting members pivoted upon one of said stays, each of said record supporting members being formed by two sheets of stiff paper of triangular shape, independent distance pieces located near the corners of said pieces of stiff paper upon which the record rests, and metallic eyelets passing through the said distance pieces and serving to secure the said sheets of stiff material thereto.

4. A rack for disk gramophone records as claimed in claim 3, wherein one of said distance pieces embodies a manipulating finger and a fixed index plate co-operates with the fingers associated with the several record supporting members.

25 5. A rack for disk gramophone records comprising two plates held in parallel spaced relationship by transverse stays, a plurality of record supporting members pivoted on one of said stays, said record supporting members being each constituted by two sheets of stiff paper each having the shape of a right-angled triangle with rounded angles, independent distance pieces located near said rounded angles, eyelets connecting said sheets 30 of stiff paper to said distance pieces, a manipulating finger on one of the distance pieces belonging to each of said record supporting members, some of said manipulating fingers being staggered in relation to other of said 35 fingers and an index plate fixed to one of said spaced plates and located in reading relation to said manipulating fingers.

40 6. A rack for disk gramophone records comprising an open frame constituted by two plates held in parallel spaced relationship by transverse rods or stays, a plurality of record supporting members of triangular form threaded upon one of said stays, said record supporting members being each constituted by two sheets of stiff paper of right-angled triangular form, a plurality of distance pieces positioned one near each corner of said sheets, metallic eyelets passing through said distance pieces serving to secure 45 the said sheets of stiff paper thereto, a manipulating finger secured to one of the distance pieces of each record supporting member and a stationary index secured to said open frame and in reading relation to all of 50 said manipulating fingers.

In witness whereof I affix my signature.

RENÉ GRANDJEAN.
